[57] CLAIM

The ornamental designs for a surgical suction regulator, as
shown and described.

DESCRIPTION

FIG. 1 is a top, front, right isometric view of a surgical
suction regulator embodying our new design in an exploded
position for clarity of illustration. It is understood that the
undisclosed top, rear, left isometric view is a mirror image
thereof;

FIG. 2 is a top plan view thereof; and,

FIG. 3 is a front elevational view thereof, the undisclosed
rear being a mirror image.

The broken lines showing tubular feedings in FIGS. 1-3 are
for illustrative purposes only and form no part of the claimed
design.
